Inventor,
Joseph Kahn,

By offield, kohlsaat, & swartz Atty.

UNITED STATES PATENT OFFICE.

JOSEPH KAHN, OF CHICAGO, ILLINOIS.

LOOSE-LEAF DEVICE.

Application filed May 31, 1922. Serial No. 564,964.

To all whom it may concern:

Be it known that I, JOSEPH KAHN, a citizen of the United States, and a resident of Chicago, in the county of Cook and State 5 of Illinois, have invented certain new and useful Improvements in Loose-Leaf Devices, of which the following is a specification.

This invention relates to improvements in loose-leaf binders, and more particularly to 10 binding or locking devices for binders of the character described.

The object of the invention is to provide a novel construction for the locking devices which coact with the binding posts to bind 15 the leaves within the binder, these devices being of hook form and adapted to be moved into and out of locking engagement with the binding posts by the addition of operating fingers conveniently located.

20 A further object of the invention is to provide simple and effective devices for limiting the movement of the locking devices in order to afford a more dependable and positive locking action.

25 Further objects and advantages will be pointed out in the course of the description which follows, and in connection with the accompanying drawings, in which—

Figure 1 is a perspective view of a binder 30 in open position, showing a preferred embodiment of the invention, and

Figure 2 is an enlarged detail view in section taken on line 2—2 of Figure 1.

The binder comprises in general the usual 35 stiff covers 1 and 2, hinged to a relatively flexible back section 3. A quantity of leaves or sheets 4 of a thickness not to exceed the space between covers is held within the binder by means of binding posts 5—5 anchored in the lower cover 2, and extending through holes punched near the margins of the leaves. At the free ends of the posts are formed eyes 5^a—5^a adapted to engage 40 fastening members 6—6 mounted upon the front or top cover 1.

In the preferred construction two binding posts and fastening members are employed, located near the lateral edges of the binder. The formation of the fastening members 50 will be understood from the following:

Secured to the inside surface of the top cover and extending along the hinged edge thereof is a plate 7 serving as a support for the fastening members, as for other purposes hereinafter set forth. If desired, the 55

plate may be concealed from view beneath the inside layer of finishing material.

Each fastening member comprises a straight shank portion 6^a terminating at its free end in a hooked end portion 6^b extending at right angles to the shank portion. At the opposite end of the shank, which extends substantially at right angles to the plate 7, is located a pin 8 whereby the fastening member is pivotally connected to the 60 plate. Integral with the shank portion and extending obliquely from the pivoted end thereof toward the near corner of the cover, is an operating finger 9 having a twisted finger piece 9^a at its end, projecting a short 65 distance beyond the adjacent edges of the leaves 4.

Integral with the plate 7, and extending along the inner edge thereof, is a tubular flange 10 projecting beyond the hinged edge 75 of the top cover 1, and extending longitudinally throughout that portion of the plate included between the fastening members 6—6. Just inwardly from the extremities of the flange 10 are formed notches 10^a—10^a 80 located opposite the fastening members, and more essentially, in registering relation with the ends of the posts 5—5, the ends of the same being slightly flattened so as to fit snugly in the notches with the eyes in registering relation with the passage formed in the tubular flange. 85

As clearly shown in Figure 1, the hooked end portions are adapted to extend into the open ends of the tubular flange through the 90 eyes of the posts registering therewith, and into the opening beyond, thereby providing a hinge-like connection permitting the necessary movement between the posts in the opening and closing of the binder. The fastening members are swung into and out of locking engagement with the posts by pressing in opposite directions upon the finger pieces 9^a with thumb or fingers. 95

In order to limit the movement of each 100 fastening member, and acting first to hold the posts in locking position; and second, to limit the withdrawal of the hooked end portion 6^a from the open end of the tubular flange 10, the following device is employed. 105

From the metal of the plate 7 just beneath the fastening member is cut a spring clip 11, based inwardly beyond the fastening member, and extending substantially at right angles thereto toward the ends of the 110

plate 7. The clip passes beneath the shank portion 6^a with its end spring upwardly and overlapping the finger 9 of the fastening member. Formed in the surface of the finger 9 is a detent 12 adapted to be engaged by the end of the clip. Moreover a stop lug 13 is formed on the clip between its end and the shank portion of the fastening member, the same being preferably struck up 10 from the metal of the clip, and in a position to be engaged by said shank portion.

The fastening members are preferably unlocked by pressing the thumbs against the finger pieces 9^a in a direction to swing the 15 shank portions outwardly and into the position shown by the lower fastening member in Fig. 1. The movement of the shank portion is limited, however, by striking against the stop lug 13, thus preventing the eye engaging portion 6^b from being entirely withdrawn from the end of the tubular flange, it being only necessary for the hooked end 6^b to clear the notch in order to release the post. Hence the hooked end of the fastening 20 member is permanently supported within the tubular flange affording a guide and bearing therefor. Pressure in the opposite direction upon the finger pieces throws the hooked ends across the notch 10^a and into locking engagement with the eyes of the post (as shown by the upper fastening member in Figure 1). In the locking position, the clip 11 springs into the detent 12, thus yieldingly retaining the posts against accidental or undesired unlocking.

The form of locking mechanism herein illustrated and described provides a particularly suitable arrangement for binders of the smaller size which require not more than 40 two binding posts, thus enabling them to be located near the ends, with the fastening members similarly located for convenient manipulation. Manifestly the structural features herein disclosed may be variously modified without departing from the spirit of the invention, and therefore I do not wish to be limited except in so far as the invention is specifically set forth in the appended claims.

50 I claim:

1. A loose-leaf binder comprising covers and a back section, a binding post mounted on one of said covers, a hooked locking member pivotally mounted on the other cover and adapted to engage the free end of said post, and a supporting plate for said locking member provided with a yieldable retaining member for holding said locking member in locking position.

60 2. A loose-leaf binder comprising covers and a back section, a binding post mounted on one of said covers, a locking member pivotally mounted on the other cover, and provided with a hooked end portion adapted to engage the free end of said post, said

locking member comprising an operating finger, and yieldable means cooperating with said finger for retaining said locking member in locking position.

3. A loose-leaf binder comprising covers 70 and a back section hingedly connected together, a binding post fixed to one of said cover members, a fastening member pivoted to the other cover member, and having a hooked end adapted to engage the free end 75 of said post, and an operating finger, and a clip yieldably engaging said finger to retain said fastening member in one position of movement.

4. A loose-leaf binder comprising covers 80 and a back section hingedly connected together, a binding post fixed to one of said cover members, a fastening member pivoted to the other cover member, and having a hooked end adapted to engage the free end 85 of said post, and an operating finger integral therewith, and a clip overlapping said finger and acting to yieldingly retain said fastening member in one position of movement.

5. A loose-leaf binder comprising covers and a back section hinged together, binding posts fixed to one cover, a plate extending along the hinged edge of the other cover, fastening members pivotally mounted on 90 said plate, and each comprising a hooked portion adapted to engage the free end of one of said posts, and a spring clip formed from said plate and overlapping said fastening member, the latter having a detent 95 adapted to receive the clip in one position of said fastening member.

6. A loose-leaf binder comprising covers and a back section hinged together, binding posts fixed at one end to one cover, a plate 105 extending along the hinged edge of the other cover, fastening members pivotally mounted on said plate, and each comprising a hooked portion adapted to engage the free end of one of said posts, and an operating 110 finger, and a spring clip formed from said plate and overlapping said operating finger, the latter having a detent engaging said finger to yieldingly retain said fastening member in one position of its movement.

7. A loose-leaf binder comprising covers and a back section hinged together, a binding post mounted on one cover, a hook shaped fastening member pivotally mounted on the other cover, and adapted to be moving 120 into and out of locking engagement with the free end of said post, an operating finger integral with said fastening member, and extending toward an adjacent free edge of said cover, and a spring clip, mounted beneath said fastening member, and overlapping said operating finger, said clip and operating finger being provided with coacting stop members for limiting the movement of 125 said fastening member.

8. A loose-leaf binder comprising covers and a back section hinged together, a binding post mounted on one cover, a plate secured along the hinged edge of the other 5 cover, hook-shaped fastening members pivotally mounted on said plate, and adapted to be moved into and out of locking engagement with the free end of one of said posts, 10 operating fingers integral with said fastening members, and spring clips cut from the plate beneath said fastening members, and overlapping said operating fingers, the latter being provided with a detent to receive said clip in the locking position of said fastening member, and said clip having a stop lug 15 adapted to be engaged by said fastening member to limit its movement out of locking position.

In witness whereof, I hereunto subscribe my name this 22nd day of May, A. D., 1922. 20

JOSEPH KAHN.
